United States Patent Office

Des. 186,123
Patented Sept. 15, 1959

186,123

PUTTER

Thomas O. Brandon, Cucamonga, Calif., assignor to A. G. Spalding & Bros., Inc., Chicopee, Mass., a corporation of Delaware

Application March 7, 1958, Serial No. 49,943

Term of patent 7 years

(Cl. D34—5)

Fig. 2 is a front end view of the putter;

Fig. 3 is a top view of the putter;

Fig. 4 is a back view of the putter; and

Fig. 5 is a sectional view taken along line 5—5 of Fig. 1.

I claim:

The ornamental design for a putter, as shown.
